WO 2004036343 A2 4/2004*Primary Examiner* — Ian Simmons*Assistant Examiner* — Mark Cavanna(74) *Attorney, Agent, or Firm* — James Creighton Wray(57) **CLAIM**

The ornamental design for a urine test device, as shown and described.

DESCRIPTION

FIG. 1 is a front, right and top perspective view of a urine test device.

FIG. 2 is a rear elevation of the urine test device shown in FIG. 1.

FIG. 3 is a left side elevation of the urine test device shown in FIGS. 1 and 2.

FIG. 4 is a front elevation of the urine test device shown in FIGS. 1-3.

FIG. 5 is a right side elevation of the urine test device shown in FIGS. 1-4.

FIG. 6 is a plan view of the urine test device shown in FIGS. 1-5; and,

FIG. 7 is a bottom view of the urine test device shown in FIGS. 1-6.
